UNITED STATES PATENT OFFICE.

JOHN E. MOULAND, OF ROBY, LANCASHIRE, ENGLAND, ASSIGNOR TO HIMSELF, JAMES ALEXANDER, AND JOSIAH B. KENDALL, BOTH OF BOSTON, MASSACHUSETTS.

STEAMSHIP.

SPECIFICATION forming part of Letters Patent No. 241,558, dated May 17, 1881.

Application filed December 20, 1880. (No model.)

To all whom it may concern:

Be it known that I, JOHN E. MOULAND, of Roby, in Lancashire, England, have invented new and useful Improvements in Steamships, 5 of which the following is a specification.

My invention relates chiefly to improvements in the form or shape of steamships for passenger and freight service.

My improved steamship is covered in at the 10 top with an elliptical or circular dome, or, so to speak, with the bulwarks extended upward and curved until they meet, the covered projections forming an oval roof and an entire covering of the vessel, and it has no outside 15 works except a smoke-stack, a wheel-house, and a wind-sail, and it is lighted from above by means of bull's-eyes or other suitable means of lighting; and that others skilled in the art may better understand the nature and use of my 20 improvement I will illustrate the same by the accompanying drawings, in which—

Figure 1 is a side elevation of the improved steamship. Fig. 2 is an end view of one-half 25 of the bow. Fig. 3 is an end view of one-half of the stern. Fig. 4 is a vertical section of the steamship in line *x x*. Fig. 5 is the hull of an ordinary vessel as heretofore built. Fig. 6 is a cross-section of the same at its greatest width.

Similar letters of reference indicate like 30 parts.

The letter A represents the steamship; B, the wheel-house; C, the wind-sail; D, the upper deck; E, the middle deck; F, the lower deck; G, the hold; K, the keel; *a*, the wheel; 35 *b b*, &c., bull's-eyes for lighting the inside; *c*, *d*, &c., ventilating-pipes.

It will be observed by examining the drawings, Figs. 1, 2, 3, 4, that the general form or shape of the steamship is oval transversely, 40 (see especially Fig. 4;) that the bow is full, and the stern-run fine, so that there is little obstruction to the smooth and easy passage of the crest of the wave over and along the body of the ship and beyond the rudder; that the 45 shape, in fact, of a cross-section of the ship is nearly like that of an egg standing on its small end from the stem of the ship to its run.

It will also be observed that the bottom of the keel is not straight from bow to stern, but

that from about one-third of the distance from 50 the bow to the stern the bottom line of the keel gradually rises toward the bow. This enables the vessel more easily to surmount the crest of the wave, and having passed the crest to fall with less dip, and rise out of the water 55 and shake herself more easily from the water—in other words, improves her buoyancy at the head or bow.

Figs. 5 and 6 of the accompanying drawings 60 illustrate the form or shape of the hull of a vessel as heretofore constructed, and a transverse section of the same at its greatest width, from which the difference in form from my invention will readily be seen.

The improvements which I seek to cover by 65 Letters Patent are confined chiefly to the external form of the steamship; the upward curve of the keel and hull from a point a third or a fourth of the distance from the bow to the stern; the full bow, and great rise of floor 70 amidships, and the absence of all top weight; the exceeding fine stern-run; the covered deck with no outside works save the wheel-house; the curved egg-shaped hull and roof, which will not ship a sea, but allow the waves to roll 75 up its sides and over its top without shipping water or slackening the speed of the vessel, and a steamship the forward part of which will always be dry.

I am aware of the English patent of Joseph 80 Burch for improvement in the forms of ships or vessels, of date 1852, No. 160, and of the patent issued to Hans Mortensen, of date April 16, 1878, No. 202,453, for improvement in torpedo-boats, and the patent issued to S. S. 85 Merriam, of date October 9, 1866, No. 58,661, for improved submarine and torpedo boats, and of the patent issued to L. D. Phillips, of date November 9, 1852, No. 9,389, for improvement in steering submarine vessels; but I do 90 not claim as my invention any of the subject-matter shown in the patents named.

What I claim as my invention, and desire to secure by Letters Patent, is—

1. A steamship of oval cross-section from 95 bow to run, and having its upper deck roofed in from bow to stern, in combination with the ventilator and wheel-house placed upon the

ridge of said roof, substantially in the manner and for the purpose shown.

2. A partly-immersed steamship of oval cross-section from stem to run, whereof the 5 bow portion of the keel is sloped upward and forward from about one-third of the distance aft from the stem, substantially as shown and described.

3. A steamship of oval cross-section from 10 stern to run, whereof the upper outline of the vertical longitudinal section is a flattened ellipse, and the lower outline thereof is a straight line from the stern-post for about two-thirds of the distance forward, and then upward by 15 a curved or inclined line to the stem, substan-

tially in the manner and for the purpose shown and described.

4. A steamship completely roofed in from stem to stern by a roof of a transverse contour, like that of the large end of an oval, and a longitudinal contour of a convex elliptical or flattened elliptical form, and having a stem which is not conical, but is of the shape of a vertical full-sided wedge with rounded corners, substantially as shown and described. 20

JOHN E. MOULAND.
